AERIAL TRAILER

Frank George Mansen, Dayton, Ohio

Application June 5, 1935, Serial No. 25,168

11 Claims. (Cl. 273—105.3)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in aerial trailers which are more particularly adapted for use as tow targets, but which may be used for other purposes, such as advertising, etc.

The primary object of the invention is the provision of an aerial tow target which may be used as such, with a high degree of efficiency in connection with anti-aircraft or other gunnery practice.

Another object of this invention is the provision of an improved aerial tow target which embodies such construction as to present sufficient area to gunners, as a target; which presents a minimum of drag to a towing aircraft, and which is sufficiently stable while being towed as to present an accurate target, without the oscillations which are sometimes attendant upon the use of conventional tow targets.

A further object of this invention is the provision of an improved aerial tow target which may be compactly assembled within a small space or compartment upon the aircraft, so that it may be efficiently launched without liability of catching in parts of the aircraft during the launching process, and yet which will efficiently deploy within a short period of time to permit of accurate use as a target for gunners, etc.

A further object of this invention is the provision of an improved aerial tow target which while embodying improved means to present a sufficient area to gunners, a minimum of drag to the aircraft, and remain stable during the towing process; yet may be manufactured at a minimum of cost due to conservation of materials.

A further object of this invention is the provision of an improved method of constructing and packing a tow target within a small compass.

Other objects and advantages of this invention will be apparent during the course of the following detailed description.

In the accompanying drawings, forming a part of this specification, and wherein similar reference characters designate corresponding parts throughout the several views,

Figure 1 is a perspective view of the tow target in its deployed condition and as it will appear to marksmen or others who are observing the same.

Figure 2 is a fragmentary side elevation of the tow target, showing the main features of construction thereof.

Figures 3, 4, 5, 6, and 7 are sectional views

taken substantially on their respective lines in Figure 2 of the drawings.

Figure 8 is a side elevation of one of the smaller inflating sleeves of the tow target, showing the construction of the same.

Figure 9 is a fragmentary sectional view taken substantially on the line 9—9 of Figure 2.

Figure 10 is a sectional view taken substantially on the line 10—10 of Figure 8.

Figure 11 is a fragmentary plan view of one of the air deflecting and inflating panels or bridles which enable immediate deployment and inflation of the tow target after it is launched.

Figure 12 is a section of webbing which is secured to the leading end of the tow target for the purpose of forming an anchoring coupling to which the tow cable is attached.

Figure 13 is a diagrammatic representation of the manner in which the various portions of the tow target are doubled and hemmed, with the reinforcing and stiffening webbing associated with the folded portions thereof.

In the drawings, wherein for the purpose of illustration is shown only a preferred embodiment of the invention, the letter A may generally designate the aerial trailer or tow target, which may include a main sleeve or body B having associated therewith a structure C comprising a plurality of inflating sleeves in an improved relation, and with which is associated a fin or bridle arrangement D for the purpose of stabilizing and directing air into the sleeves B and C. A tow cable E is connected at the leading end of the bridle arrangement D.

The main body sleeve or tube B may be of a single piece of material, although it is preferably made of a plurality of lengthwise panels which are suitably stitched together to provide a tube which may vary in diameter, as deployed. Preferably, for ordinary gunnery purposes, the inflated diameter of the main sleeve may approximate thirty-nine inches in diameter, although this distance may vary for various purposes. For instance, for ordinary gun target use it may be

smaller than for anti-aircraft target practice, and when used for other purposes, the aerial trailer, such as for advertising purposes, may vary considerably in size. For ordinary target uses the main sleeve B may vary between twenty-six inches and thirty-nine inches in inflated diameter, and the length thereof may vary between nine and eighteen feet, although these dimensions are not to be regarded as limitations upon the inventive structural features.

The trailing end of the main sleeve has a

ring-shaped section 20 which is appropriately stitched thereto as at 21, as by doubling the material of the sleeve upon itself to provide at the extreme trailing end a circumferential passageway 22 wherein is disposed a section of rope or cable 23. Preferably this cable 23 is of one-quarter inch manila yacht rope, although it may be of elastic material, similar to the elastic restricting cable which is used in the vents of parachutes. The purpose of the rope or cable material 23 is to restrict the outlet at the trailing end of the sleeve B. The cable or rope 23 has a normal diameter which is somewhat less than the diameter of the passageway 24 thru the sleeve B, and in this respect puckers the ring 20 at the trailing end of the sleeve B, to provide as a restricted outlet opening 30. Thus the necessary drag is created upon the target as it is towed by the aircraft, to properly deploy the target in a path which can be predetermined. The diameter of the outlet opening 30 as defined by the rope or cable 23 is such as to permit the air to spill through the target without unnecessary restriction upon the speed of the aircraft.

Referring to the intermediate section of the tow target, which may be appropriately termed the small sleeve section C, the same is provided in order to insure an accurate and efficient launching of the tow target; to permit of the folding of the tow target into small compass; and to permit instant inflation. To that end this section C consists of a plurality of small diametered sleeves 28, which are preferably of the same material as the sleeve B. At their rear ends these sleeves or tubes 28 are connected in the forward open end of the large body sleeve B and extend therefrom forwardly exteriorly of the sleeve B: the same being connected in a symmetrical arrangement at their forward ends and having the bridle construction D attached thereto.

The construction of each of the sleeves 28 is indicated in Figures 5 and 8 of the drawings. For their major length each consists of a single ply of material. The diameter of these tubes is of course governed by the diameter of the large tube or sleeve B. It is preferred to use six of them, arranged so that when the tow target is inflated their axes will lie parallel with each other and with the tow axis of the aerial trailer. At their forward ends each of the sleeves 28 is preferably doubled upon itself to provide a multi-fold hem 30^a, which may be stitched in any approved manner, in order to provide a circumferential passageway for a rigid preferably metallic ring 31. These rings 31 are all of the same diameter. Eyelets or grommets 32 are provided radially through this hem portion 30^a in such relation that when the sleeves 28 are placed in a symmetrical circular arrangement, laces 35, shown in Figure 9, may be employed to connect the said ring ends of the sleeves 28 together, and so that the sleeves may be swiveled at these ring ends. This enables the rigid rings 31 to be folded one upon the other in order to pack the tow target into a small compass and in such orderly fashion that it may be quickly deployed. The rings 31 may be of any approved construction, as is shown in Figure 9, and they may be formed by bending the material upon itself at its ends and soldering it as at 38 after wrapping it with wire.

At their rear ends the sleeves 28 are each doubled outwardly upon themselves, to provide a double ply portion 37 of about six inches in length which is intended to extend into the open

forward end of the main sleeve B so as to direct the air flowing through the smaller sleeve into the larger sleeve. Strong linen webbing 40 is stitched circumferentially about the sleeve 28 at the forward end of the portion 37 which extends into the large sleeve. At its forward end the main sleeve B is also provided with strong linen webbing 41, suitably stitched thereto. The tubes or sleeves 28 are so arranged at their rear ends in the open end of the main sleeve B that the webbing 40 lies in the same plane as the webbing 41 of the main sleeve, and, as indicated in Figure 7, the rear ends of the small sleeves 28 at this location are suitably stitched, as shown at 50, so as to permanently connect the small sleeves 28 at their rear ends with the forward end of the main sleeve B. Of course the portions 37 of the sleeves 28 which extend into the forward end of the main sleeve are preferably not otherwise connected together or to the main sleeve.

Referring to the bridle construction D for guiding movement of the air into the sleeves of the aerial trailer, the same comprises a series of elongated plane surfaces 60 joined together at their longitudinal edges upon the tow axis of the trailer and radiating therefrom. These surfaces are each of the shape of right angled triangles. Their apices are connected together at the forward tow cable connecting end of the target and the hypotenuse edges thereof are located outermost. There are six of these fins, one for each of the sleeves 28, and at their rear ends they extend slightly into the forward ends of the respective sleeves with which they are associated, diametrically across the inside of the respective sleeves. Thus the fin or plane surface for each small sleeve 28 not only directs the air flow into the sleeve, but divides the air stream as it flows into the small sleeve; thus preventing eddies and eccentricities in the air stream flow. By reference to Figures 3 and 11 of the drawings it will be seen that these six fins of the bridle construction are in reality formed of three sections 59 of flexible fabric. These sections of fabric are of identical construction. They are each in the form of an isosceles triangle, except at their base ends. At the base or rear, each of these sections 59, as indicated in Figure 11, is provided with a pair of plane extensions 70, of a width sufficient to permit the extension thereof into the open ends of the sleeves 28. Each section 59 of fabric is reinforced along the sides thereof, at its apex, and around the marginal edges of the extensions 70 with strong linen webbing. The three sections 59 are joined together upon a line which would normally be the altitude of the triangular sections 59, and which lies in the axis of tow of the aerial trailer, as can readily be understood by reference to Figures 1 and 2 of the drawings. The length of each extension portion 70 may of course vary. Preferably it varies from six to ten inches and these extensions project into the forward open ends of the smaller sleeves 28; the opposite webbing reinforced edges of each of the extensions 70 being stitched suitably to the material of the sleeve, at diametrically opposed points, so as to provide a diaphragm-like partition in the open end of the sleeve, diametrically thereacross, as indicated in Figure 9 of the drawings. As indicated in Figure 11 of the drawings each of the fabric sections 59 at each of the partition extensions 70 is provided with webbing strips 80 which are overlapped at the outer sides of the respective sleeves with which the extensions 70 are

associated, and stitched thereto, as indicated in the various views of the drawings. This provides a very firm and strong connection between the bridle construction and the small sleeve section, with the fins 60 of the bridle construction so arranged as to accurately divide the air stream and guide the movement of the air flow into the tubes 28.

Each fabric section 59 of the bridle construction is provided at its outer end with a piece of 10 webbing. This webbing is shown at 90 in Figure 12 of the drawings and it is stitched to the apex end of the section 59 so as to provide an open loop at said apex, as indicated in Figure 2 of the drawings. These pieces of webbing 90 are then 15 all stitched securely together to provide a very strong eye through which the tow cable or rope E is connected in any approved manner.

From the foregoing description it can readily be understood that an aerial trailer has been 20 provided, which is particularly well adapted for use as a tow target for use in connection with anti-aircraft or other gunnery practice. For aerial gunnery the target will be towed at distances of about six hundred feet and for anti-aircraft practice a distance of about three thousand feet. Due to the improved construction of 25 this tow target, sufficient area is presented to the gunner so as to furnish an adequate target. There is a minimum of drag upon the towing airplane, and the target is stable, without unnecessary oscillations. The fabric of which the target is constructed is preferably mercerised cotton airplane cloth, and that is true for each of the sections B, C, and D. All of these sections are 30 entirely flexible, so far as the cloth is concerned, and so far as the linen webbing, except for the rigid shaping rings 31 which are disposed in the forward ends of the smaller sleeves 28. The diameter of these sleeves may of course vary. Preferably it is less than $\frac{1}{3}$ of the diameter of 35 the large sleeve B. Thus it can be seen that the entire target may be folded into a very small compass. Due to the connection of the rings 31 they may be folded one upon the other and the fabric packed in orderly fashion so that the entire target may be launched through a small opening in the rear cockpit of a towing airplane or other aircraft. Of course the rings 31 overlap upon 40 each other and provide a bundle which is not appreciably greater than the diameter of a single ring 31. These rigid rings 31 are provided for the necessary stiffening at the mouth end of the small tubes so as to obtain instant inflation as soon as the target is launched. The fin or bridle 45 construction D of course insures not only a proper division of air stream into the tubes 28, but the diaphragm in the smaller ends of the tubes acts as an immediate straightener for unfolding the rings into position for inflation.

The floating cord 23 at the rear end of the tow target permits the use of a large vent opening and thus reduces drag so that it is not appreciably greater than that of a straight opened sleeve.

The large sleeve B permits of a simple design of target and reduces the fabric required to a reasonable amount. It will of course be possible to utilize a series of long sleeves, such as provided in the section C, of small diameter, all attached 70 together, and do away with the larger sleeve section B, but such construction would require an excessive amount of material. In order to give an idea of proportion of length, the section B in length may be about six times the length of the 75

section C, and the section D may be about four times the length of the section C. These proportions may of course vary.

Various changes in the steps of the method of 5 packing the tow target, and changes in the shape, size, and arrangement of parts of the improved target may be made to the form of invention herein shown and described, without departing from the spirit of the invention or the scope of the claims.

I claim:

1. An aerial trailer comprising as the main body thereof an elongated sleeve construction having an air spill passageway therethrough, bridle means for directing movement of air into the sleeve connected with the forward end of the sleeve and extending forwardly therefrom, said bridle construction comprising a plurality of plane fins, said sleeve construction including a plurality of small diametered sleeves arranged in parallelism and having individual fins of the bridle construction extending into the open mouth ends of said sleeves for directing air flow thereinto.

2. An aerial trailer comprising an elongated sleeve-like structure open at both ends and having a relatively long collapsible sleeve-like body open at both ends, a plurality of parallel air current directing sleeve-like cells opening into the body sleeve at the fore end thereof, each cell being open at its fore and aft ends, stabilizing vanes at the fore ends of said cell sleeves for directing and stabilizing air draft therethrough, said vanes being arranged in relative radial relation and in diametrical intersection with the cell-like sleeves.

3. An aerial trailer comprising an elongated sleeve-like structure open at both ends and having a relatively long collapsible sleeve-like body open at both ends, a plurality of parallel air current directing sleeve-like cells opening into the body sleeve at the fore end thereof, each cell being open at its fore and aft ends, stabilizing vanes at the fore ends of said cell sleeves for directing and stabilizing air draft therethrough, said vanes being arranged in relative radial relation and in diametrical intersection with each of the cell-like sleeves, a tow cable connected at the fore ends of said vanes, and the rear end of the main body sleeve being provided with a choked spill opening.

4. An aerial trailer comprising an elongated main body sleeve of flexible material which is relatively long to be used as a trailer for general target practice and of a nature to be collapsed bodily upon itself laterally and longitudinally, said sleeve having a passageway therethrough opening at the forward end and with a choked spill opening at the rear end thereof, a plurality of relatively shorter elongated collapsible sleeve sections connected at their rear ends within the fore end of the first mentioned sleeve and each projecting beyond the fore end of the first mentioned sleeve, said plurality of smaller sleeve sections having passageways therethrough opening at the fore and rear ends thereof, and vane means at the fore ends of said group of smaller sleeve sections to insure the direction of air thereinto.

5. An aerial tow target comprising an elongated flexible sleeve-like body which has a length dimension many times that of the cross-dimension thereof, said sleeve being provided with a passageway therethrough open at the fore and aft ends of the sleeve, means for attaching the

fore end of the sleeve to a towing vehicle, and resilient means at the periphery of the aft opening of the target normally tending to restrict the opening and vary its size according to the pressure of the air as it spills through said opening.

6. An aerial tow target comprising an elongated flexible sleeve-like body which has a length dimension many times that of the cross dimension thereof, said sleeve being provided with a passageway therethrough open at the fore and aft ends of the sleeve, means for attaching the fore end of the sleeve to a towing vehicle, and resilient means at the periphery of the aft opening of the target normally tending to restrict the opening and vary its size according to the pressure of the air as it spills through said opening, said resilient means comprising a floating elastic band peripherally surrounding the air spill opening.

7. An aerial trailer comprising a plurality of flexible and longitudinally collapsible sleeves, each of which is cylindrical in formation, means grouping said sleeves together in a cylindrical arrangement, and an elongated collapsible vane construction connected with said sleeves and extending forwardly therefrom.

8. An aerial trailer comprising a plurality of flexible and longitudinally collapsible sleeves, each of which is cylindrical in formation, means grouping said sleeves together in a cylindrical arrangement, and an elongated collapsible vane construction including a plurality of vanes connected with said sleeves and extending forwardly therefrom, the plane of the vanes transversely

intersecting the passageways through said sleeve sections for dividing the air stream travel therethrough.

9. An aerial trailer comprising a plurality of flexible and longitudinally collapsible sleeves, each of which is cylindrical in formation, means grouping said sleeves together in a cylindrical arrangement, an elongated collapsible vane construction connected with said sleeves and extending forwardly therefrom and an elongated large diameter main body sleeve having the above mentioned cylindrical arranged smaller sleeves disposed in the fore part thereof for directing travel of air therethrough.

10. An aerial trailer comprising a plurality of flexible cylindrical collapsible sleeves open at their fore and rear ends, means grouping said sleeves together in a cylindrical arrangement, a rigid ring in the fore end of each sleeve for holding the sleeves open at their mouths, and means for directing air into the open ends of said sleeves.

11. An aerial trailer comprising a plurality of flexible cylindrical collapsible sleeves open at their fore and rear ends, means grouping said sleeves together in a cylindrical arrangement, a rigid ring in the fore end of each sleeve for holding the sleeves open at their mouths, and means for directing air into the open ends of said sleeves, said rings being connected together so that the sleeves when they are collapsed may be arranged with the rings in a superposed stacked relation.

FRANK GEORGE MANSON.
